UNITED STATES PATENT OFFICE.

HERBERT L. LITTLE, OF JEFFERSONVILLE, OHIO.

HOG-OILER.

1,295,908.

Specification of Letters Patent.

Patented Mar. 4, 1919.

Application filed January 25, 1918. Serial No. 213,755.

To all whom it may concern:

Be it known that I, HERBERT L. LITTLE, a citizen of the United States, residing at Jeffersonville, in the county of Fayette and 5 State of Ohio, have invented a new and useful Hog-Oiler, of which the following is a specification.

This invention relates to hog oilers, one of its objects being to provide a rubbing element which, when pressed against by a hog, 10 will operate means for discharging a limited amount of oil which will be guided downwardly onto the hog.

A further object is to provide means for 15 collecting surplus oil discharged from the machine, said surplus being used for oiling a roller designed to apply oil to a hog.

A still further object is to provide means whereby a constant supply of oil may be provided, the same being prevented, however, 20 from discharging except as used.

With the foregoing and other objects in view which will appear as the description proceeds, the invention resides in the combination and arrangement of parts and in the 25 details of construction hereinafter described and claimed, it being understood that changes in the precise embodiment of the invention herein disclosed can be made within 30 the scope of what is claimed, without departing from the spirit of the invention.

In the accompanying drawings the preferred form of the invention has been shown.

In said drawings:-

35 Figure 1 is a view partly in front elevation and partly in transverse section of one side portion of a side oiler embodying the present improvements.

Fig. 2 is a section on line 2—2 of Fig. 1.
40 Fig. 3 is a transverse section through the rubbing bar.

Referring to the figures by characters of reference 1 designates a supporting frame having a base 2 on which is arranged a collecting tank 3. Mounted above and extending partly into this tank is a roller 4 designed as a means for transferring oil from the tank to the belly of a hog passing over the roller.

45 50 Supported above the collecting tank 3 is a distributing tank 5 and opening downwardly into this distributing tank is the outflow tube 6 of a supply tank 7. Said outflow tube has one or more outlet openings 8 through which oil will flow into the tank 5 until the level of the oil in said tank rises

above the opening whereupon further supply of oil to the tank 5 will be cut off.

Pivottally connected to the lower portion of one side of the frame 1 is a rubbing bar 9 the upper end portion of which is provided with spaced arms 10 the free ends of which are connected by a cross pin 11 or the like. That end of the bar 9 between the arms 10 is inclined as shown at 12 in Fig. 1 so as to 60 direct downwardly and inwardly any oil which may be discharged onto the bar and between the arms 10. Longitudinal grooves 13 are formed in the inner side of the bar 9 and communicate with the space between 65 the arms 10 so that the oil guided along the inclined portion 12 will be directed into the grooves 13. The lower end of the bar 9 is offset so as to overhang one end portion of the tank 3 whereby any surplus oil leaving 70 the grooves 13 will gravitate into the tank 3.

The arms 10 are so shaped that when the bar 9 is in its normal position with said arms resting against one end of the tank 5, the rod or pin 11 will overhang the tank 5. 75 This bar or pin 11 extends across a dipping spoon 14 which is pivotally mounted in the tank 5 as shown at 15 and has an upwardly extending tongue 16 provided with an opening 17 which communicates with the recess 80 in the spoon 14. The arms 10 straddle the tongue 16 and the pin 11 extends across said tongue. Under normal conditions the spoon 14 rests upon the bottom of the tank 5 but, when the bar 9 is thrust laterally out of its 85 normal position, the pin 11 will pull on the tongue 16 and will cause the spoon 14 to swing upwardly to the position indicated by dotted lines in Fig. 1. This will cause the contents of the spoon to pour therefrom 90 through the opening 17 and onto a tongue or apron 18 which extends from the upper portion of the tank 5 and into the space between the arms 10. Consequently the oil thus discharged will flow into the space 95 between the arms 10 and onto the inclined face 12 and thence be distributed into the grooves 13.

From the foregoing it is thought that the 100 operation of the device will be clearly understood. When a hog passes over the roller 4 oil will be applied thereto as hereinbefore described. When the hog rubs against the bar 9, said bar will be shifted laterally as shown by dotted lines in Fig. 1, thus causing the spoon 14 to swing upwardly and discharge its contents onto the bar 9 so that the 105 110

oil will thus be directed against the hog. Surplus oil will flow into the tank 3 and be supplied to the roller 4. As the level of the oil in the distributing tank 5 is lowered, additional oil will be supplied from the tank 7.

If desired the apparatus may be provided with a rubbing bar at each side thereof in which event a depending guide 19 may be 10 hung within the frame so as to cause the hogs to pass close to one of the bars.

What is claimed is:—

1. The combination with a distributing tank, and a supplying tank opening therein 15 to and having an outlet adapted to be sealed by the liquid contents of the distributing tank, of an apron depending from the upper edge of one wall of the distributing tank, a rubbing bar pivotally mounted at its lower 20 end and provided at its upper end, with spaced arms straddling the apron and overhanging a portion of the distributing tank, 25 a cross pin connecting the upper ends of the arms, a spoon tiltably mounted within the tank and having an upwardly extending tongue projecting between the arms and back of the pin, there being an opening in the tongue for directing the contents of the spoon, when tilted onto the apron, the piv-

oted bar being provided with an inclined 30 portion for guiding the delivered liquid from the apron to one surface of the bar.

2. The combination with a collecting tank, and a distributing tank thereabove having an inclined apron extending from the upper 35 edge of one wall thereof, of a rubbing bar pivotally mounted at one side of the collecting tank and normally overhanging said tank, said bar having spaced arms at its upper end straddling the apron and normally overhanging the distributing tank, a pin connecting the arms at the upper ends, a spoon tiltably mounted in the distributing tank, and a tongue extending upwardly from one end of the spoon and back of the pin, 40 said tongue having an outlet opening for directing liquid from the tilted spoon to the apron, there being an inclined surface on the bar between the arms for directing delivered liquid to the under side of the normally inclined bar.

In testimony that I claim the foregoing as my own, I have hereto affixed my signature in the presence of two witnesses.

HERBERT L. LITTLE.
